UNITED STATES PATENT OFFICE.

MALCOLM F. McCONNELL, OF STEUBENVILLE, OHIO.

ADJUSTING MECHANISM FOR ROLLING-MILLS.

1,218,286.

Specification of Letters Patent.

Patented Mar. 6, 1917.

Application filed September 22, 1916. Serial No. 121,612.

To all whom it may concern:

Be it known that I, MALCOLM F. McCONNELL, a citizen of the United States, residing in Steubenville, in the county of Jefferson and State of Ohio, have invented certain new and useful Improvements in Adjusting Mechanisms for Rolling-Mills, of which the following is a specification.

My invention relates to the construction of roll adjusting mechanisms for rolling mills and more particularly the roll adjusting mechanism of two-high reversing mills, universal plate mills, and similar apparatus having a movable top roll which is adjusted toward or away from its opposite roll after each reducing pass of the metal rolled in such mills.

One object of my invention is to provide a roll adjusting mechanism having improved means whereby the movable roll is adjusted toward and away from its opposing roll.

Another object of the invention is the provision of a roll adjusting mechanism having the novel constructions, combinations, and arrangement of parts shown in the drawings, more fully described herein-after and specifically pointed out in the appended claims.

Referring now to the drawings forming part of this specification, in which my invention is shown applied for use with the "screw down" mechanism of a two-high reversing blooming mill or mill used in rolling ingots into blooms, slabs, billets, and similar materials, Figure 1 is a side elevation.

Fig. 2 is a plan, partly in section of the apparatus of Fig. 1.

Fig. 3 is a face elevation, partly in section of one form of clutch mechanism used with my invention.

Fig. 4 is a radial section of the clutch mechanism of Fig. 3, the section being taken on the line 4-4 of Fig. 3.

In the accompanying drawings, the vertically movable top roll A and the lower roll (which is not shown) are rotatably mounted in bearing blocks and the bearing blocks are secured in the windows of the roll housings B, B, in the usual and well known manner. The bearing blocks for the adjustable top or upper roll A are secured to the lower ends of the threaded stems or screws d, d, of which one extends downwardly through an opening in the housings

into the upper end of each housing window into holding engagement with one of the bearing blocks.

Mounted on top of each housing B is an internally threaded nut D through which the threaded portion of the stems or screws d project, the nuts D being rotatably secured to the tops of the housings so as to prevent relative lifting thereof when rotated.

Each of the housing nuts D is provided with a worm wheel E and each worm wheel is in mesh with a worm F on the horizontal worm shaft G. The worm wheels E are fastened to the nuts D so as to rotate the nuts when the worm wheels are turned by the worms F and the worms are keyed or otherwise secured to the worm shaft G so as to rotate with the shaft. When the nuts D are rotated the stems or screws d, d, are moved lengthwise and the upper roll A which is secured to the screws through the roll bearing blocks is adjusted vertically toward and away from the bottom or lower roll.

It sometimes happens that the rolls are jammed together when adjusting the top roll toward the bottom one so tightly that the motor has not power enough to again lift the top roll. Thereby much time is lost and expense incurred. I propose to avoid this difficulty by interposing between the motor and the roll a clutch or equivalent device which will work positively in one direction and impositively in the other.

For example, I have shown a clutch on the worm driving shaft which provides only a frictional engagement between the two parts G and G' into which the worm shaft 95 is divided when a downward adjustment of the roll is taking place, and a positive engagement during a lifting adjustment. It is impossible with such a clutch to jam the upper roll down so tightly that the motor 100 cannot lift it.

The clutch may be of various types adapted to work this way. In Fig. 4 there is shown a drum K keyed on the shaft section G' and carrying flat rings L engaging longitudinal grooves in the drum, and between the rings L are rings M engaging similar grooves in a hub N on the shaft section G. The head O of the drum holds the clutch rings in place and they are held in close 110 frictional engagement by one or more adjustable springs P. When the section G' of

the shaft is rotated it has a strong frictional driving engagement with the section G, but not so strong as to force the two rolls into such tight engagement as to be beyond the power of the motor to separate them and lift the top roll.

On the head O of the drum are mounted a number of heavy pawls Q backed by abutments R against which they are drawn by springs S. The hub N extends outward beyond the head of the drum and has shoulders T in positions to engage the pawls Q. When the shaft-section G and the drum are turned in the direction of the full line arrow in Fig. 3 the drive on the shaft-section G is only frictional, the pawls riding over the shoulders T in case of any slipping in the clutch.

When the drum is turned in the direction of the dotted line arrow, however, the clutch can slip only until the pawls strike the shoulders T, after which the drive is positive. In the case illustrated this positive drive is in the direction to lift the upper roll.

Though I have described with great particularity of detail a particular machine embodying my invention, yet it is not to be

understood therefrom that the invention is restricted to the particular machine disclosed. Various modifications in detail and in the arrangement of parts may be made by those skilled in the art without departing from the invention.

I claim:—

1. A rolling mill having a motor-operated roll-adjusting mechanism including a clutch between the motor and the roll, said clutch adapted to work positively in one direction and impositively in the other.

2. A rolling mill having a motor-operated screw-down mechanism including a clutch between the motor and the roll, said clutch adapted to work positively in lifting the roll and impositively in screwing it down.

3. A rolling mill having a motor-operated screw-down mechanism including worm gearing acting on the bearings of a roll, a shaft driven by the motor and actuating said worm gearing and a clutch in said shaft adapted to transmit the force of the motor positively in lifting the roll and impositively in forcing it down.

In witness whereof I have hereunto signed my name.

MALCOLM F. McCONNELL.
